UNITED STATES PATENT OFFICE

HERBERT W. ORNDOFF, OF NEW ORLEANS, LOUISIANA, ASSIGNOR TO THE E. V. BEN-JAMIN CO., INC., OF NEW ORLEANS, LOUISIANA, A CORPORATION OF LOUISIANA, TRADING AS MAGINNIS COTTON MILLS

JUSTIFYING MEANS FOR USE IN CONNECTION WITH PRINTING AND SIMILAR DEVICES

Application filed October 8, 1928. Serial No. 311,151.

The present invention relates to justifying devices for assuring the feeding of a sheet to a printing or other drum at a proper timed relationship with respect to the movement of the drum itself.

The structure according to the present invention is particularly designed for employment in conjunction with blanks which have been cut from a web of material and delivered by endless tapes to the feeding system for the printing drum, and proposes to bring the front edge of such blanks into position on a line parallel to the axis of the drum, holding it in such position until the gripping members on the printing drum will engage and hold the blank while carrying it along with the drum in the rotation of the latter.

Another feature of the present invention is the provision of an especially simple device of this character, which operates to support the blank away from the printing drum and yet hold it so that it may be readily and immediately seized and carried forward by the aforesaid gripping members.

A further feature is the provision of justifying means including retaining rollers which normally hold back the front edge of the blank but which yield readily to permit the withdrawal of the blank beneath the rollers without undue friction from the justifying device upon the surface of the blanks as it travels beneath them in its passage along with the printing or other drum.

With these and other objects in view as will appear in the course of the following specification and claims, I have shown an illustrative example of construction of a printing machine embodying the present invention, on the accompanying drawings, in which:

Figure 1 is a fragmentary end elevation of the feeding system in conjunction with a printing drum and a tape delivery device.

Fig. 2 is a view corresponding to Fig. 1 but illustrating a section taken at a right angle to the axis of the printing drum, and thus representing a further view of certain of the parts shown in Fig. 1.

Fig. 3 is a fragmentary plan view on a

slightly smaller scale, with certain parts omitted for greater clearness.

Fig. 4 is a detail view on a larger scale, of the support for an individual justifying roller.

Fig. 5 is a corresponding end view of the same part, seen from the edge of the roller.

In these drawings, the standard 10 of the illustrated printing machine carries suitable journals for the printing roll 11. The sheets or blanks to be printed are brought forward, from right to left in Figs. 1 and 2, on the upper flight of the tapes 12, these tapes passing over the guide roller 13 adjacent the surface of the printing drum 11 and returning on the lower flight to a position in which a further blank may be engaged. The upper delivery tapes 14 pass in their lower flight in substantially parallel relationship and opposite the respective lower conveying tapes 12, being first diverted slightly upward by the guide rollers 15, and finally passing over the guide roller 16 and returning in their upper flight. The respective guide rollers 13, 15 and 16 are supported on slotted members 13^a, 15^a, 16^a whereby the tension on these tapes may be controlled as desired in the usual manner. On the standard 10 of the machine are mounted the supporting brackets 17 which receive the transverse bar 18 at the ends of the printing drum 11, so that the structure is supported near to but spaced from the surface of this printing drum. The transverse bar 18 supports a guide plate 19 which is substantially in extension of the upper flight of the tapes 12 so that a sheet S traveling along between the tapes 12 and 14 is deflected by the guide plate 19 along its upper surface. The left hand edge of the plate 19, as seen in Fig. 2, is bent upwardly and spaced a small distance from the actual surface of the printing drum 11 itself. This edge has portions cut away from place to place as shown in Fig. 3, opposite the gripping members or fingers 20 which are mounted on a transverse shaft 21 of the printing drum 11 itself, and are suitably controlled by cam or other devices in well known manner, so that the gripping fingers are caused to be opened before they pass

through the notches 19 in the plate 19 (Fig. 100).

3), and these gripping fingers are closed down upon an associated part of the printing drum 11 the moment that the rearward edge of the gripping finger has passed the predetermined 5 position of the front edge of the blank S, thereby pinching or gripping this front edge of the blank S between the respective fingers 20 and the periphery of the printing drum 11 in well known manner.

10 A further bracket 22 on the machine frame 10 supports a transverse rod 23 having fixed thereto the plate 24 at a desired angular position. Mounted on this plate 24 opposite the 15 projections 19^b of the plate 19 are respective brackets 25 for justifying rollers 26 which are preferably formed of light material such as aluminum, and being narrow in width of face and adapted by their position and arrangement to relatively fit into the slots 27 20 in the extensions 19^b (Figs. 2 and 3). Each of these rollers 26 has the axle 28 passed therethrough, the ends of the axle being received in a respective notch 29 formed in the lower part of the bracket 25, this notch being 25 closed by a plate 30. The lower end of each of the brackets 25 is bifurcated and the inwardly directed surfaces of the two tines fit closely to the ends of the respective rollers 26 so that the roller is substantially prevented 30 from rocking, but is permitted to move up and down by the play of its axle 28 in the notches 29. A slot 31 is formed at the upper end of the respective brackets 27, so that the respective bracket may be adjusted 35 and locked by the respective cap screws 32 passing through this slot and into the plate 24.

40 In operation, as a blank S is brought forward by the conveyor tapes 12 and 14 which continue to move at a proper speed, being equivalent to the peripheral speed of the printing drum 11, the front edge of the blank comes against the peripheral surfaces of the series of justifying rollers 26, which are then 45 occupying their lowermost position in the slots 27. The front edge of the advancing blank is therefore stopped definitely at this point, and the entire front edge is alined or justified along a line extending parallel to the 50 axis of the printing drum 11. In the timing of the operation of the various parts, it will be understood that it is customary to provide an interval of delay from the moment of expected arrival of the front edge of this blank 55 S at this position, for this justification to occur in case some part of the blank has been detained. By reason of the independent positioning of the conveyor tapes 12 and 14, and their simultaneous driving, the justification 60 is accurately effected.

65 At the end of this allotted time interval, the gripping members 20 on the printing drum 11 are caused to close upon the front edge of this blank S. Heretofore, the tapes have 65 continued to advance the rear portion of the

blank, but have not acted upon or moved the front edge beyond the blocked position of alignment established by the reception of the justifying rollers 26 in the slots 27. The gripping members 20 seize the front edge, 70 and carry it down upon the printing drum 11 and thereby grip the same sufficiently so that during the continued forward or counter-clockwise movement of the printing drum 11, the entire blank is drawn forward 75 along the plate 19 and over the projections 19^b thereof, the drag exerted by the gripping of the clamping fingers 20 causing this front edge to be pulled beneath the justifying rollers 26 so that the latter are caused to rise up 80 out of their respective slots 27 and travel along the upper surface of the blank S. By the journaled arrangement of the rollers substantially little friction is afforded to the blank S while so drawn, and by reason of the continuing advancement of the tapes 12 and 14, very little pull is necessary to bring the blank forward and upon the printing drum 11 for printing, for example, by the printing roller 40 in Fig. 1.

85 As soon as the rear edge of the blank S has passed, the several justifying rollers 26 drop into their slots 27 again under the influence of gravity, and by its engagement with the front and rear walls of the respective notch 27, the respective roller is effectively prevented from spinning, so that a second blank closely following the blank which has just been fed onto the printing drum 11, will not tend to ride under the respective justifying roller 26.

90 In particular, it will be noted that the justifying rollers are entirely independent one of another and have no mechanical connection thereto, their operation being determined solely by the movement of the blank S as effected by the gripping members 20 on the printing drum, and by the action of gravity when the blank has passed.

95 While the invention has been described in an illustrative form of execution, it will be understood that it is not limited solely to such employment, but may be used in many ways within the scope of the appended 100 claims.

110 What I claim as new and desire to secure by Letters Patent is:

115 1. In a mechanism to feed sheets to a rotating drum having a sheet gripper and means to operate the same to grip a sheet at a predetermined point of the rotation, a continuously driven feeding conveyor, a guide member to carry the sheets from the conveyor to the drum and including a portion extending beyond the gripping point of the gripper and spaced axially of said drum from the path of the gripper, and gravitationally held and sheet operated justifying means cooperating with the extended portion of said guide 120 125 130

member to retain the sheet until it has been seized by said gripper.

2. In a mechanism to feed sheets to a rotating drum having a sheet gripper and means to operate the same to grip a sheet at a predetermined point of the rotation, a continuously driven feeding conveyor, a guide member to carry the sheets from the conveyor to the drum and including portions extending beyond the gripping point of the gripper and spaced axially of the drum at either side of the path of the gripper, said extended portions of said member having slots therein alined in a direction parallel to the axis of the drum, and a justifying device entering each slot and cooperating with said member so that when the sheet moves over the guide member it is retained by said justifying device until it has been seized by said gripper.

3. In a mechanism to feed sheets to a rotating drum having a sheet gripper and means to operate the same to grip a sheet at a predetermined point of the rotation, a feeding conveyor, a guide member to carry the sheets from the conveyor to the drum and including portions extending beyond the gripping point of the gripper and spaced axially of said drum from the path of the gripper, individual justifying means cooperating with each of said extended portions to retain the sheet until it has been seized by the gripper, said justifying means being operated by the sheet when seized by the gripper to release the sheet for movement with the rotating drum.

4. In a mechanism for feeding sheets to a rotating drum having a sheet gripper, a continuously driven feeding conveyor, a guide member to carry the sheets from the conveyor to the drum, said guide member having slots therein alined in a direction parallel to the axis of the drum, independent members gravitationally held in said slots and cooperating therewith in such position to retain the individual sheet until it has been seized by said gripper, said members being individually displaced upward by the sheet when the latter is moved forward by the gripper whereby to permit the sheet to move beneath said members.

5. In a mechanism to feed sheets to a moving member having a sheet gripper, a continuously driven feeding conveyor, a guide member to carry the sheets from the conveyor to the drum, said member having a plurality of slots therein, and a plurality of justifying rollers normally located in said slots and frictionally engaging with the walls thereof to prevent rotation of the rollers, said rollers and member cooperating to retain the individual sheet until it has been seized by said gripper, said rollers thereupon being raised by the sheet during its forward movement and rolling over the sheet during the

passage of the latter over the guide member to the drum.

6. In a mechanism to feed sheets to a rotating drum having a sheet gripper, a continuously driven feeding conveyor, a guide member to carry the sheets from the conveyor to the drum, said member having projecting portions extending along the periphery of the drum in spaced relationship, said grippers passing between said portions, said portions having slots alined in a direction parallel to the axis of the drum, independent justifying means adapted to be moved downward by gravity to enter said slots from above when no sheet is located therebeneath so that a sheet fed by the conveyor is retained until it has been seized by said gripper, said member being raised by said sheet when moved by said gripper whereby to permit the drawing of the sheet over the guide member by said gripper.

7. In a mechanism to feed sheets to a rotating drum having a sheet gripper, a feeding conveyor, a guide member to carry the sheets from the conveyor to the drum, said guide members having a plurality of slots, a plurality of brackets, each of said brackets having notches therein, a closing plate to enclose each of said notches, a plurality of rollers each having an axle, said axles being movable in said notches under the action of gravity, and being adapted to enter said slots to cooperate therewith to retain an individual sheet until it has been seized by said gripper, and thereby raised by said sheet against the action of gravity so that the sheet may pass therebeneath, said bracket preventing the rocking of the respective roller and axle about their axes.

In testimony whereof, I affix my signature. 105
HERBERT W. ORNDOFF.
